Des. 189,567
Patented Jan. 10, 1961

189,567

TOOTH-BRUSH HOLDER

Stanley James Clayton, 30 Blacklow Brow, Huyton-with-Roby, near Liverpool, England

Filed Jan. 21, 1959, Ser. No. 54,262

Claims priority, application Great Britain Sept. 24, 1958

Term of patent 14 years

(Cl. D4—3)

Fig. 1.

Fig. 2.

Fig. 3.

Fig. 1 is a front perspective view of a tooth-brush holder in open position showing my new design;

Fig. 2 is a rear perspective view taken from the bottom and left side thereof, the right side not shown being substantially the same; and

Fig. 3 is a front perspective view taken from the bottom and left side thereof, but with the cover in closed position.

I claim:

The ornamental design for a tooth-brush holder, as shown and described.
